UNITED STATES PATENT OFFICE.

HUGH P. McMILLAN, OF BALTIMORE, MARYLAND, ASSIGNOR TO WM. A. TOTTLE & CO.,
A FIRM COMPOSED OF WILLIAM A. TOTTLE AND MORTON P. TOTTLE, OF BALTIMORE,
MARYLAND.

BRUSH.

1,009,082.

Specification of Letters Patent. Patented Nov. 21, 1911.

Application filed October 11, 1910. Serial No. 586,427.

To all whom it may concern:

Be it known that I, HUGH P. McMILLAN, a citizen of the United States, residing at Baltimore, State of Maryland, have invented 5 certain new and useful Improvements in Brushes, of which the following is a specification.

This invention relates to improvements in brushes and has particular reference to circular forms of brushes for painting, varnishing 10 and lather purposes.

The object of the invention is to improve the construction of brushes of this kind; to make them strong and durable; to 15 surely retain the bristles in place and to protect the lower end of the handle against the action of liquids that will swell the wood and burst the brush at the butt-ends of the bristles.

20 With these and other objects in view the invention is illustrated in the accompanying drawing in which,—

Figure 1, shows an elevation of a brush constructed in accordance with the invention. Fig. 2, is an enlarged sectional detail of the lower end of the handle and the means for securing the handle and bristles together. Fig. 3, is a sectional plan view of the brush,—the section being taken on the 25 line 3—3 of Fig. 2. Fig. 4, is a top plan view of the detached metal socket, and Fig. 5, is a side elevation of the same.

In the drawing, 1, designates a handle having a central circular plug, 2, at its lower 30 end; a horizontal annular shoulder, 3, extending laterally from and around the said plug and a tapered exterior wall, 4, extending upwardly from said annular shoulder. The taper of the handle is such as to decrease the diameter of the same as it 35 recedes upwardly from the shoulder, 3. The central circular plug, 2, is provided with exterior screw threads, 5, for a purpose presently to be described.

40 A collar, 6, encircles the lower tapering end of the handle and has a central opening, 7, which increases in diameter from the upper to the lower side in order that it may snugly fit the handle and the lower surface 45 of the collar is preferably flush with the horizontal shoulder, 3, at the upper end of the plug.

A metal socket member, 8, has a circular 50 central socket, 9, which has interior threads, 10, that form corresponding exterior circum-

ferential grooves, 11, and at the upper end said socket member is provided with a circular annular flange, 12, which preferably has a plurality of perforations, 13, therein that are disposed about the central socket. This 60 socket member is screwed onto the circular plug, 2, until its circular flange, 12, seats against the annular shoulder, 3, of the handle and projects beneath the lower side of the collar, 6. Bristles, 14, are disposed 65 about the circular socket and their upper ends are bound together by means of a suitable cement or rubber which oozes into the perforations, 13, in the socket flange and which also fills the circumferential exterior 70 grooves, 11, in the central socket wherein it will set and harden with the result that it forms a union between the socket member and bristles. A suitable ferrule, 15, encircles the upper end of the bunch of bristles; the 75 circular edge of the socket flange and also the vertical circumferential wall of the collar so that nails, 16, may be driven through the upper portion of the ferrule and also through the collar into the handle to retain 80 those parts in rigid relation. A fastening, 17, also extends through the lower portion of the ferrule and the cemented bunch of bristles and also through a perforation, 18, 85 in the central metal socket and through the handle plug whereby to permanently lock those parts together.

Having thus described my invention what I claim and desire to secure by Letters Patent is,—

1. A brush comprising a handle having an encircling collar adjacent to but above its lower end and also having a circular metal socket engaging the lower end of the handle below the collar,—said socket having an annular flange about its upper open end which extends beneath the collar, bristles around the circular socket, a ferrule having its upper portion encircling the collar and its lower portion encircling the bristles, fastenings extending through the ferrule and collar and entering the handle and a fastening 95 extending through the ferrule, the bunch of bristles, the circular socket and the lower end of the handle.

2. A brush comprising a tapered handle having a circular threaded plug which projects below the tapered portion thereof, a collar having a tapered central opening to engage the tapered handle, a circular thread- 100 105 110

ed socket member engaging said threaded plug of the handle, bristles around the socket and below the collar, a ferrule about the collar and upper ends of the bristles, 5 means for securing the ferrule to the collar and means for securing the bristles to the socket members and plug.

In testimony whereof I affix my signature in presence of two witnesses.

HUGH P. McMILLAN.
